[57] CLAIM

The ornamental design for a hair comb, as shown and described.

DESCRIPTION

FIG. 1 is a front elevation of a hair comb showing my new design, the rear being a mirror image;

FIG. 2 is a top plan view of the comb of FIG. 1;

FIG. 3 is a bottom plan view of FIG. 1;

FIG. 4 is a left side elevation taken from the left in FIG. 1;

FIG. 5 is a right side elevation taken from the right of FIG. 1;

FIG. 6 is a front elevation of a hair comb showing a modified form of my new design, the rear being a mirror image;

FIG. 7 is a top plan view of the comb of FIG. 6;

FIG. 8 is a bottom plan view of FIG. 6;

FIG. 9 is a left side elevation taken from the left in FIG. 6;

FIG. 10 is a right side elevation taken from the right of FIG. 6;

FIG. 11 is a front elevation of a hair comb showing a second modified form of my new design, the rear being a mirror image;

FIG. 12 is a top plan view of the comb of FIG. 11;

FIG. 13 is a bottom plan view of FIG. 11;

FIG. 14 is a left side elevation taken from the left in FIG. 11; and

FIG. 15 is a right side elevation taken from the right of FIG. 11.
